UNITED STATES PATENT OFFICE.

CLARENCE Q. PAYNE, OF NEW YORK N. Y.

PNEUMATIC CONCENTRATING-TABLE.

1,212,393.

Specification of Letters Patent. Patented Jan. 16, 1917.

Application filed August 18, 1916. Serial No. 115,590.

To all whom it may concern:

Be it known that I, CLARENCE Q. PAYNE, a citizen of the United States of America, residing in the borough of Manhattan, city, 5 county and State of New York, have invented certain new and useful Improvements in Pneumatic Concentrating Tables, of which the following is a full and true description.

10 My invention relates to improvements in that type of concentrating table which separates associated minerals from each other, or crushed ores from their gangues, in a dry state, by reason of differences in their 15 specific gravities, when they are acted on by air under pressure while being subjected to mechanical agitation.

It consists in the combination of a novel 20 and improved form of table top with improved means for separating minerals of different specific gravities, after they have been arranged in layers or strata by means of air pressure and mechanical agitation upon the surface of said table top.

25 In a patent numbered 1,068,163, granted to me July 22, 1913, I have described and claimed a novel medium for the previous top of a pneumatic concentrating table, whereby greater durability, as well as more 30 uniform effects, are procured in the treatment and separation of various ore mixtures.

35 My present application is a modification and improvement of the above mentioned patent, and is specifically concerned with a new and useful combination of means for removing the separated products from the table after they have been stratified, with the aforesaid novel and durable top, where- 40 by a more efficient and satisfactory separation is obtained than has heretofore been possible.

45 In the accompanying illustrations Figures 1 and 2 show a concentrating table in part sectional elevation and plan, in which my invention is embodied. Fig. 3 shows a sectional view across the table top. Fig. 4 illustrates a portion of the table-deck on a larger scale than Fig. 1, and Fig. 50 5 illustrates diagrammatically the principle

involved in my invention. Figs. 3 and 5 are illustrations of Fig. 1 on an enlarged scale.

In Figs. 1 and 2 the form of concentrating table illustrated is so designed that the table 55 deck can be given an inclination both in a longitudinal direction, and also in a transverse direction, so that the stratified products may be separated from each other in distinct bands, conveyed lengthwise of the 60 table by the shaking motion of the table, and then collected at the end and side of the table, as indicated in Fig. 2. For this purpose the table is supported by any convenient tilting mechanism, such as shown in 65 Figs. 1 and 2. Here the upper end of the table is held by a sleeve, or short hollow shaft 10 in the bracket support 11 to the foundation frame 12. The end of sleeve 10 supports the bracket 13, which rotates about 70 it and to which is bolted the spring-plate 14. The latter in turn supports the bearings 15, 15 at its extreme ends, and these support the ends of the shafts 16, 16 which are held by brackets 17, 17 to the deck 75 frame of the table.

The bracket 13 has an extension on its lower side, which carries the segment of a worm wheel. The latter engages a worm which is mounted on the shaft 18, and is re- 80 volved by means of the hand-wheel 19. In this way the table deck can be tilted transversely to a considerable angle by the rotation of the hand-wheel while at the same time it can be moved rapidly back and forth 85 by the slight bending of the spring plate 14 at its ends, which supports about one-half the weight of the table.

The lower end of the table may be prefer- 90 ably supported by a single hinged rocker-arm, or shaft, so as to obtain, in effect a three point support for the table-deck, and thus avoid unnecessary vibration. The rocker shaft permits a forward motion of 95 the table by rotation about the pivot 21, and also a transverse inclination by rotation about the pivot 22. At the same time a cer- 100 tain amount of vertical adjustment can be secured by means of the hand-wheel-nuts 23 and threaded shaft 20. In this way the

table-deck can be given an inclination longitudinally as well as transversely. A reciprocating motion may be conveniently imparted to the table-deck by means of a cam 24, or other suitable device for giving it a slow forward and quick return motion, the object being to agitate and also propel the material fed upon the table-deck rapidly lengthwise of the table.

10 As shown in Fig. 1 the cam 24 is mounted upon the shaft 25, and raises the roller 26, which rotates upon a shaft held in the bell-crank-lever 27, to which the connecting rod 28 is attached. This connecting rod is held 15 at its other end to the pivoted bracket 29, which is riveted to the end of the table frame. To absorb the shock of the rapid reversal of the table-deck, and to maintain the roller 26 always in contact with the cam 24, spiral springs 30, 30 are supported between fixed abutments on the bracket 11 and wings on the bell-crank-lever 27. The compression of the springs can be varied by means of suitable bolts and washers as 25 shown in Fig. 2. The amount of motion to be given the table-deck and the speed of the latter, or number of shakes per minute, will vary with the degree of fineness of the material to be treated.

30 The table-deck of my concentrating table, as shown in part section in Fig. 1, and the cross section in Fig. 4, is composed of porous silica plates 31, or a like mineral septum, through which air under pressure is made 35 to pass. The joints and ends of the plates are carefully cemented so that the air from the inclosure below them can only pass through the body of the plates. These plates are supported by means of light T 40 irons 32, which are riveted to the channel iron frame of the table. The latter forms the four sides of a box, of which the silica plates form the top. The bottom of the box is inclosed by a thin sheet iron plate 45 closely riveted to the channel iron flanges so as to make air tight joints. Air is admitted to the under side of the concentrating table by means of a pipe 34, which is connected with a pressure fan, not shown in 50 the drawings.

The table is fed at its upper end from any convenient hopper 35. The ore-mixture should be carefully sized in advance, depending however on the difference in the 55 specific gravity of the minerals to be separated. As it is caused to travel lengthwise of the table by the quick return stroke of the latter, the combined effect of the upward air currents through the fine pores and 60 openings of the silica plates, or similar mineral septum, with the agitation due to the shaking motion of the table, causes the minerals of the ore mixture to separate and to occupy superposed layers or strata 65 on the table-deck, the heavy mineral form-

ing the lower layer while the light mineral forms the upper layer, as indicated in the diagram Fig. 5.

I have found that the different minerals thus stratified can be best separated from each other by establishing a difference in the rate of flow between the upper and lower layers of the ore-sheet, so that the shaking motion can induce the layers to flow along divergent paths of travel as they are conveyed diagonally across the table top under the combined influence of the shaking motion and the side tilt of the table-deck. This result can be secured in accordance with my invention by causing certain portions of the mineral septum to be made impervious to air along narrow areas spaced lengthwise of the table-deck.

A convenient construction, embodying my invention, consists in cutting shallow 85 grooves 36, 36 in the top of the mineral septum which forms the table-deck, and then filling these grooves with an impervious cement flush with the surface of the table deck as shown in Fig. 3. For this 90 purpose Portland cement may be employed or any similar cement whose ingredients are approximately as hard as the material of the mineral septum itself, so as to be equally 95 resistant to wear. In passing upward 100 through the mineral septum, the air is then obstructed along the areas of the impervious grooves. The latter may be placed either parallel with the longitudinal motion of the table, or preferably at a slight angle to it, 105 as indicated in Fig. 2.

Fig. 5 illustrates diagrammatically more clearly the resulting effect of my invention in causing the separation of superposed layers of minerals to pursue different rates of 110 flow: The lower shaded area here represents the heavier mineral, and the upper shaded area the light mineral, which have thus been stratified by the joint action of mechanical agitation and the sorting action 115 of air under pressure passing through the ore-mixture. The underlying principle involved in this stratifying effect is that of "hindered settling". When the ore-sheet thus stratified encounters one of the impervious areas of the table-deck, its lower portion is more retarded in passing over it than its upper portion. This is partly due to the greater frictional resistance there encountered, partly to the more complete 120 cessation of the lifting effect of the air at the bottom than at the top of the ore-sheet, (as illustrated by the arrows), and partly to the lessened resistance to motion of a particle situated at the top of the ore-sheet, as 125 compared with one at the bottom. If we illustrate the combined forces thus acting on a particle situated at A, by the line A B, and on a particle at C by the line C D, we can thus illustrate diagrammatically the 130

different rate of flow which can be established between the upper and lower layers of an ore-sheet by the retarding effect upon the lower layers when the ore-sheet is made 5 to travel across an impervious area in the table-deck. This effect can be heightened by so placing the impervious areas that they run lengthwise of the table-deck, or approximately so.

10 In passing over the pervious areas, the effect upon the ore-sheet is primarily to stratify the minerals it contains along superposed layers, while in passing over the impervious areas, the effect is primarily to 15 cause a separating action between the upper and lower strata, by establishing a difference in their rate of movement across these areas. By repeating this action a great many times in causing the ore sheet to pass diagonally 20 across a series of alternately pervious and impervious areas of the table-deck, I have found that a very efficient separation can be made between minerals of different specific gravities.

25 The operation of my table is as follows: Air from a pressure fan is conveyed through a pipe 34 to the inclosure below the table deck, and is then allowed to pass through the pervious mineral septum of the table-deck under a regulated pressure. At the same time the table while in a transversely inclined position, is given a rapid reciprocating motion by means of the cam and lever, or similar head motion mechanism, 30 driven by a belt from an outside source of power. The material to be separated is fed in a dry state in a regulated stream from a hopper 35. It is preferably first sized before it is fed upon the table; *i. e.*, it is 35 passed over screens in order to reduce the difference in the diameters of the particles to a predetermined ratio. In traveling lengthwise, and across the inclined surface of the table-deck, the ore-mixture encounters a series of alternately pervious and 40 impervious areas of the mineral septum which forms the surface of the table. While passing over the former, the combined action of the upward air current and the mechanical agitation of the particles, due to 45 the shaking motion of the table, causes the heavier particles to settle through the agitated mass, and form the bottom layer of the ore-sheet resting on the table-deck. The 50 lighter particles, on the other hand, work their way upward and form the top layer of the ore-sheet as indicated in the sketch Fig. 5. In passing over the impervious areas 55 of the table-deck, however, the stratifying action is temporarily interrupted, and a difference in the rate of travel between the upper and lower layers of the ore-sheet is established. This causes the upper and 60 lower layers to progress along divergent paths of travel as they are propelled length-

wise of the table-deck. These effects being repeated a great many times by reason of the subdivision of the surface into alternately pervious and impervious areas, the different minerals composing the ore-sheet 70 are separated from each other, and made to travel in radiating bands, as shown in the plan view of the table in Fig. 2, by the areas bounded by the broken lines. The separated products are then collected by the 75 guide-pieces whose position can be adjusted along the end and lower side of the table, as shown in Fig. 2, and discharged into different receptacles. In order to maintain a suitable thickness of the ore-sheet along its 80 upper edge, where the heavy mineral collects, I have found it desirable to employ banking strips for this purpose, as shown at 87, 87 in Fig. 2.

Having thus described my invention, I 85 claim:

1. In a pneumatic concentrating table, a table deck composed of a mineral septum, pervious to air under pressure and provided with a series of grooves along its upper surface filled with cementitious material, in combination, with means for conveying the material to be separated across said table deck while subjected jointly to mechanical agitation and to air under pressure, substantially as described.

2. In a pneumatic concentrating table, a table deck composed of a mineral septum, pervious to air under pressure and provided with a series of grooves along its upper surface filled with cementitious material, in combination with means for blowing air through the pervious areas of the table deck, means for agitating the table deck in an inclined position, and means for feeding the material to be separated upon the surface of the table deck, substantially as described.

3. In a pneumatic concentrating table, a table deck composed of a mineral septum, pervious to air under pressure, and provided with a series of parallel grooves along its upper surface filled with cementitious material, in combination with means for agitating said table deck in a transversely inclined position, means for blowing air through the pervious areas of said table deck, means for feeding the material to be separated upon the surface of said table deck, stratifying the minerals contained in the material thus fed into horizontal layers by the joint action of mechanical agitation, and of air under pressure, and then separating the strata from each other by causing them to travel over the alternately cemented and uncemented areas of said table deck, substantially as described.

4. In a pneumatic concentrating table, a table deck composed of plates of accreted mineral particles forming a mineral septum and having a series of parallel grooves filled

with cement, in combination with means for passing air through the uncemented areas of said table deck, means for reciprocating the table in a transversely inclined position, 5 means for feeding the material to be separated upon said table deck, stratifying the minerals thus fed into horizontal layers by the joint action of air under pressure and of mechanical agitation, and then separat-

ing the strata by causing them to travel diagonally over the alternately cemented and uncemented areas of said table deck, substantially as described. 10

CLARENCE Q. PAYNE.
